UNITED STATES PATENT OFFICE.

GUSTAV KOMAREK, OF CHICAGO, ILLINOIS, ASSIGNOR TO ST. LOUIS BRIQUETTE MACHINE COMPANY, OF ST. LOUIS, MISSOURI, A CORPORATION OF MISSOURI.

MATERIAL-FEEDER FOR BRIQUET-MACHINES.

1,293,475.

Specification of Letters Patent.

Patented Feb. 4, 1919.

Application filed November 28, 1917. Serial No. 204,363.

To all whom it may concern:

Be it known that I, GUSTAV KOMAREK, a citizen of the United States, residing at Chicago, Illinois, have invented a certain new and useful Improvement in Material-Feeders for Briquet-Machines, of which the following is a full, clear, and exact description, such as will enable others skilled in the art to which it appertains to make and use the same, reference being had to the accompanying drawings, forming part of this specification.

My invention relates generally to briquet machines and more particularly to an apparatus for feeding the material from which the briquets are formed, directly to the briquet forming press or machine, and the particular type of feeder herein shown and described is designed for use in connection with the type of briquet machine disclosed in my copending patent application filed February 5, 1918, Serial Number 215,445.

The briquet press disclosed in my copending application just referred to includes a pair of coöperating rolls, the peripheries of which are provided with mold cavities and each roll being carried by a pair of pivoted frames or levers, and it is the principal object of my present invention to mount a material feeding box and feeding mechanism upon the roll carrying frames or levers so that the opening or outlet from said feed-box always occupies the same relative position with respect to the periphery of the roll.

Further objects of my invention are, to provide a comparatively simple and easily operated feeding mechanism which will be positive and efficient in performing its intended functions; to provide simple means for accurately regulating the feed of the material from the box to the mold cavities in the periphery of the briquet forming roll, and further, to provide simple means for pressing the plastic material into the mold cavities, thereby insuring the filling of said mold cavities, which action is necessary to effect the production of briquets, the bodies of which are of uniform density.

With the foregoing and other objects in view, my invention consists in certain novel features of construction and arrangement of parts, hereinafter more fully described and

claimed, and illustrated in the accompanying drawings, in which—

Figure 1 is a side elevational view of a briquet material feeding apparatus of my improved construction, the same being associated with the forming roll of a briquet press;

Fig. 2 is an elevational view taken looking in the direction indicated by the arrow 2 in Fig. 1, with parts in section;

Fig. 3 is a vertical section taken approximately on the line 3—3 of Fig. 2;

Fig. 4 is a horizontal section taken approximately on the line 4—4 of Fig. 3.

Referring by numerals to the accompanying drawings, 10 designates one of the rolls of a briquet press, the same being mounted on a shaft 11, which latter is journaled in suitable bearings formed in a pair of substantially upright frames or levers 12, the latter being fulcrumed near their lower ends upon a horizontally disposed shaft (not shown).

Located on the periphery of this roll is a series of rings 13 in which are formed mold cavities, and arranged between these rings are chains 14, the links of which serve as end walls for the mold cavities. The links of these chains are substantially wider than the grooves between the mold rings 13; consequently said chains project a substantial distance beyond the peripheries of said rings. (See Fig. 3).

Fixed in any suitable manner to the upper ends of the levers 12 is the upper part 15 of the feeding box said upper part being preferably cast in a single piece and comprising a pair of side walls and a pair of end walls.

Fixed in any suitable manner to the lower portions of the walls of the box member 15 and depending therefrom is the lower part 16 of the box, the same comprising a pair of side walls 17 and end walls 18. The lower portion of the end wall 17 is curved inwardly as designated by 19 and the lower portion of the opposite end wall 18 is curved gradually inward as designated by 20.

The space between the lower ends of the inwardly curved portions 19 and 20 forms an outlet or feed opening 21 and when the box is properly positioned on the levers 12,

said feed opening is positioned directly above the upper edges of the chains 14. (See Fig. 3.)

(See Fig. 3.) Journalized in suitable bearings formed in the side walls 16 of the lower part of the box are shafts 22 and 23, said shafts extending through one of the levers 12 and being provided with meshing pinions 24. One of these shafts extends through the lever 12 on the opposite side of the machine and is provided with a sprocket wheel 25 upon which operates a sprocket chain 26, the latter passing around a suitable sprocket wheel (not shown), which is carried by the shaft on which the levers or frames 12 are fulcrumed. Those portions of the shafts 23 within the feed box are provided with radially disposed fingers 27 which, when the device is in operation, serve to effectively stir the briquetting material within the lower portion of said box and cause the same to feed evenly out through opening 21.

Arranged for horizontal sliding movement beneath the inwardly projecting portion 19 of wall 17 is a plate 28, the same being held for operation between suitable guides 29, and formed integral with the inner edge of this plate is a series of fingers 30 which project into the spaces between the chains 14.

30 the chains 14. When plate 28 is moved backward or forward, these fingers are projected into or withdrawn from the spaces between the chains with the result that the amount of material fed into the mold cavities of the forming drum is very accurately regulated. 35 A portion of plate 28

Carried by the outer portion of plate 28 is a transversely disposed shaft 30^a and loosely connected to the ends thereof are the lower ends of a pair of links 31. The upper ends of these links are fixed to the end portions of a rock shaft 32 which is journaled in suitable bearings 33 on the lower portion of wall 17. Fixed to one end of this rock shaft 32 is an upwardly projecting lever 34, the upper end thereof being bifurcated and terminating adjacent to the upper portion of box member 16.

Pivots mounted on the upper portion of one of the side walls of box member 15 is the inner end of a horizontally disposed rod 35, and loosely mounted on the outer portion thereof is a collar 36 to which is pivotally connected the bifurcated upper end 50 of lever 34. Interposed between this collar 34 and the connection for the inner end of said rod is a comparatively stiff compression spring 37. The outer end portion of rod 35 is threaded and screw-seated thereon 55 upon is a hand wheel 38 against which collar 36 normally bears.

Journalized in suitable bearings 39 on the lower portion of end wall 17 is a transversely disposed shaft 40 and fixed thereto in any suitable manner are depending links

41 in which are journaled the ends of a transverse shaft 42. Carried by this shaft 42 are rollers 43, the peripheral portions of which extend into the spaces between the chains 14 on the briquet forming roll 10. 70

Obviously, there are the same number of rollers 43 as there are teeth 30 on plate 28 and the corresponding pairs of teeth and rollers occupy the same vertical planes.

rollers occupy the same vertical position. Secured to one end of shaft 40 is an upwardly projecting lever 44, the upper end being bifurcated and pivotally connected to a collar 45, which latter is loosely mounted on a rod 46. The inner end of this rod is pivotally connected to the upper portion of the side wall of the box member 15 and the outer end of said rod is threaded and receives a hand wheel 47 against which the collar 46 normally bears. Interposed between collar 45 and the inner end of a rod 46 is a compression spring 48.

When the press with which my improved feeder is associated is in operation, sprocket chain 26 is driven, thereby imparting rotary movement to one of the shafts 23, and this motion is transmitted to the other shaft through the gear wheels 24. Thus the shafts 22 and 23 are rotated toward each other with the result that the stirring fingers 27 are operated within the lower portion of the box or container, and consequently, the material which is in plastic form will be fed downwardly through opening 21 and fill the mold cavities in the rings 13 and the spaces between chains 14. 10 13 20 10

the spaces between chains 11. Plate 28 provided with the fingers 30 can be moved toward or away from the pressure roll by proper manipulation of hand wheel 38, and thus the amount of material fed onto said roll can be very accurately 105 regulated.

regulated. The rollers 43 operating in the spaces between the chains 14 press the material into the mold cavities, thereby insuring the proper filling of said cavities just prior to the time the briquets are subjected to the highest pressure of the forming rolls, and by proper manipulation of the hand wheel 47, these rollers can be moved toward or away from the chain carrying roll 10. Thus it will be seen that plate 28 performs the functions of a gate or scraper which may be readily adjusted to regulate the amount of material fed into the spaces between the chains and further, that the rollers 43 provide simple means for pressing the material thus fed between said chains, into the mold cavities, and as a result of this accurate feed and the forcing of the material into the mold cavities, all of the briquets formed between the rolls have practically the same density when finally compressed. This insures a uniform product and is effective in reducing to a minimum the breakage of briquets while being handled.

It will be readily understood that minor changes in the size, form and construction of the various parts of my improved feeder can be made and substituted for those herein shown and described, without departing from the spirit of my invention, the scope of which is set forth in the appended claims.

I claim:

1. The herein-described feeder for briquet machines having a pressure roll in the periphery of which is formed circumferentially disposed grooves, said feeder comprising a container provided with a discharge opening, means for regulating the size of the discharge opening from said box to control the discharge of material through said opening, and a series of spaced material pressing rollers associated with said container.
2. In a feeder for briquet machines having a pressure roll in the periphery of which is formed circumferentially disposed grooves, a container provided with a discharge opening, an adjustable member arranged on said container to one side of said discharge opening, fingers projecting from said member into said opening and into the grooves of the pressure roll with which the feeder is associated, and a material pressure roller arranged beneath and in the same vertical plane with each finger.
3. In a feeder for briquet machines having a pressure roll, the periphery of which is provided with circumferentially disposed grooves, the combination with a container provided with a discharge opening, of a series of spring-held adjustable rollers spaced apart and arranged below the discharge opening in the container, and which rollers are adapted to press the material discharging from the container into grooves in the periphery of the pressure roll of the machine with which the feeder is associated.
4. In a feeder for briquet machines having a pressure roll in the periphery of which is formed circumferentially disposed grooves, a container provided with a discharge opening, an adjustable member arranged on said container to one side of said discharge opening, yielding pressure means for resisting the opening movement of said adjustable member, a series of fingers projecting from

said adjustable member into the discharge opening, which fingers are adapted to enter grooves in the periphery of the pressure roll of the machine with which the feeder is associated, and a series of spaced material pressing rollers mounted for operation below said adjustable member.

5. In a feeder for briquet machines having a pressure roll in the periphery of which is formed circumferentially disposed grooves, a container provided with a discharge opening, an adjustable member arranged on said container to one side of said discharge opening, yielding pressure means for resisting the opening movement of said adjustable member, a series of fingers projecting from said adjustable member into the discharge opening, which fingers are adapted to enter grooves in the periphery of the pressure roll of the machine with which the feeder is associated, a series of spaced material pressing rollers mounted for operation below said adjustable member, and yielding pressure means for resisting the movement of said pressure rollers away from the outlet opening.

6. In a feeder for briquet machines having a pressure roll in the periphery of which is formed circumferentially disposed grooves, a container provided with a discharge opening, means arranged for movement on said container to one side of said opening, manually operable means for moving said member away from the opening in the container, yielding pressure means for resisting the movement of said member away from the opening, a series of spaced material pressing rollers arranged for operation below said plate, which rollers are adapted to enter the grooves in the pressure roll of the briquet machine, manually operable means for adjusting the position of the rollers with respect to the opening, and yielding pressure means for resisting the movement of the rollers away from the discharge opening.

In testimony whereof I hereunto affix my signature this 23rd day of November, 1917.

GUSTAV KOMAREK.

Witness:

LAURA E. SMITH.
